INKING MECHANISM FOR MULTICOLOR PRINTING PRESSES

Oscar H. Banker, Philadelphia, Pa.

Original application July 7, 1927, Serial No. 203,880. Divided and this application September 24, 1932, Serial No. 634,672

7 Claims. (Cl. 101—186)

One object of my invention is to devise, in conjunction with a multi-color printing press machine, a novel construction and arrangement of inking mechanism wherein a continuous motion is imparted in the same direction to the controlling elements of the inking mechanism, thus eliminating the necessity, as has heretofore been deemed necessary, of employing reciprocatory or oscillatory movements.

10 A further object of my invention is to devise novel means for providing variable vibrating strokes of the vibrating rolls, and for effecting the adjustment of such variable vibrations.

15 A further object of my invention is to devise a novel turn over mechanism for the inking rolls, whereby, on a predetermined extent of revolution, they are automatically locked in position, and on a further predetermined revolution they are automatically unlocked, and novel means are provided for causing the inking rolls to cooperate in timed relation with the impression forms to which the color they carry is adapted to be applied.

20 With the above and other objects in view, as will hereinafter more clearly appear, my invention comprehends a novel inking mechanism for multi-color printing presses.

25 It further comprehends a novel multi-color printing press wherein the type beds can all carry impression forms and travel in a continuous path so that during a single cycle the proper color is applied to all of the impression forms.

30 It further comprehends a novel construction and arrangement of inking mechanism wherein the inking rolls and their controlling elements have imparted to them a continuous rotary motion.

35 It further comprehends a novel turn over mechanism for the inking mechanism wherein novel means are provided for locking and unlocking the inking rolls at the proper times.

40 Other novel features of construction and advantage will hereinafter more clearly appear in the detailed description and the appended claims.

45 For the purpose of illustrating the invention I have shown in the accompanying drawings a typical embodiment of it, which, in practice, will give satisfactory and reliable results. It is, however, to be understood that the various instrumentalities of which my invention consists can be variously arranged and organized, and my invention is not limited to the exact arrangement and organization of these instrumentalities, as herein set forth.

50 Figure 1 is a top plan view of a multi-color printing press embodying my invention.

Figure 2 is a section on line 2—2 of Figure 1.
Figure 3 is a section on line 3—3 of Figure 1.

Figure 4 is a rear elevation of the machine partly in section, the section being taken substantially on line 4—4 of Figure 1.

Figure 5 is an end view of a pair of inking or form rollers.

Figure 6 is a plan view of the construction seen in Figure 5, but showing in addition the vibrating mechanism.

Figure 7 is a plan view of portions of the vibrating mechanism.

Figure 8 is a plan view of the turn over mechanism of one set of inking rollers.

Figure 9 is an end elevation of the construction seen in Figure 8.

Figure 10 is a plan view of the turn over mechanism of another set of inking rollers, and showing in addition a lifting cam and its cooperating mechanism.

Figure 11 is a top plan view of a portion of the inking mechanism showing more particularly, and on a larger scale, the driving means for the inking rolls.

Figure 12 is a side elevation of the vibration means for the inking rolls of set C.

Similar numerals of reference indicate corresponding parts.

Referring to the drawings:—

1 designates the frame of the machine, the construction and arrangement of which may vary widely in practice. The base portion of the machine is ordinarily a casting in order to give sufficient rigidity to the operation mechanism and eliminate, as much as possible, the vibrating to which machines of this character are subjected.

The frame is provided with inner and outer anti-friction supports 2 and 3 respectively, which form tracks on which the type beds 4, travel. The type beds are linked together by means of a continuous chain 5, and this chain is of the roller type, having the rolls 6 which travel between spaced guides 7, which are arranged in such a manner that they form an elliptical path.

Each type bed 4 carries a longitudinally extending rack 8 having rack teeth on its bottom end adapted to be driven by a pinion 9, carried by a shaft 10, suitably journaled in the frame of the machine. The shaft 10 at its opposite end has fixed to it a gear 11, see Figure 3, which meshes with a driving pinion 12 carried by a shaft 13, suitably journaled in the machine frame. The shaft 13 is provided with a sprocket 14 around which passes a silent chain 15 which also passes around a sprocket 16 on the shaft of a motor 17.

50

55

It will thus be seen that when the motor is running the driving pinion 9 is continuously driven, thereby due to the provision of the chain 5 imparting a travel to all of the type beds to cause them to move in an elliptical path.

5 The rack bars 8 are arranged in such a manner that as one rack bar moves out of engagement with the pinion 8 the next rack bar is at the same time beginning its engagement with it, 10 so that an accurate and continuous movement is imparted to all of the type beds as they are all interconnected by the chain 5.

In accordance with my present invention it is not necessary to employ an idle type bed and all 15 of the type beds can carry impression forms 18.

I have thus far described the construction for causing the travel of the type beds.

19 designates the impression cylinder which is carried by a shaft 29 journalled in the machine frame and provided with a gear 21 which meshes with and is driven by the gear 11.

The impression cylinder is provided with any desired or conventional form of sheet gripping mechanism 22.

25 As illustrated, the sheets to be printed are fed into the machine by hand on a feeding table 23 and moved forwardly against an adjustable guide 24 which operates in the well known and conventional manner, so that, at the proper time, when 30 the grippers 22 are in position to receive the sheet, front guides 24 are automatically lifted out, and the grippers, gripping the sheet 25, fixes it relatively to the impression cylinder and carries it around with it.

35 At each revolution of the impression cylinder one color is applied to the sheet which it carries. During the last impression, the grippers 22 are released and the stripper fingers 26 are brought into action in the usual and conventional manner 40 in order to cause the sheets to be stripped from the impression cylinder and transferred to grippers 27. The grippers 27 are in an open position to receive the sheet, the opening of the grippers being caused by a stationary cam 28. The 45 grippers close and grip the paper and start to carry the sheet with them, and the travel of the grippers is at the same peripheral speed as that of the impression cylinder 19, this being essential to prevent the bulging or stretching of the sheets 50 during the time of transfer, since the back end of this sheet is still being received on the impression form.

The grippers 27 are carried by an endless chain 30 which travels around sprocket wheels 31. The 55 shaft 32 of one sprocket wheel 31, is provided with a gear 33 which meshes with an idler 31' which in turn meshes with the gear 21 thereby imparting a drive to the gripper carrying chain 30.

Continuing the description of the transfer 60 mechanism, the end sprocket wheel 31 has mounted in proximity to it a curved guide 34. After a sheet carrying gripper travels around the end sprocket 31, it is brought to the lower stretch 65 of the chain so that the position of the grippers 60 is now reversed, and the sheet carried by it is turned bottom side up, thus the printed side of the sheet is turned up. As the gripper carrying a sheet 25 comes into contact with a stationary cam 35, such gripper is released and the sheet 70 strikes the guide 36 and drops to the receiving table 37, so that the sheets pile one above the other with their printed faces on top. An adjustable guide 38 is also provided which operates in the usual and conventional manner to effect 75 the piling of the printed sheets on the table 37.

This table, as illustrated, is carried by a separate standard 39.

The table 37 in practice, can be lowered step by step as the sheets are piled up, by means of any conventional type of table controlled mechanism, 5 and I have therefore deemed it unnecessary in the present instance to describe in detail the construction and arrangement of such mechanism which is well known to anyone skilled in this art.

The inking mechanism

In accordance with my present construction, I provide inking mechanism whereby each impression form receives at the proper time its individual color. For the purpose of illustration only, I have shown the machine as adapted to print five colors and I have therefore shown five impression forms with the necessary inking mechanism for such forms.

20 The shaft 13, shown in Figures 1 and 3, has fixed to it a pinion 40. The left hand portion of Figure 4, is shown in section, while the right hand portion is shown in side elevation, and it will be understood that I employ two sets of driving 25 mechanisms for the inking rolls, and such driving mechanisms are substantially identical.

The pinion 40 meshes with a gear 41, journalled on a stud 42 carried by the machine frame. This stud 42 meshes with a gear 43 carried by a stud 44 on the machine frame. The gear 43 meshes with a gear 45 which is loosely mounted on a shaft 46, journalled in the machine frame.

The gear 45 meshes with a pinion 47 mounted on a stud 48 carried by an arm 49, which at its 35 inner end is fixed to the shaft 46. The pinion 47 meshes with a pinion 50 which is fixed to a pinion 51 to revolve in unison therewith, and both of the pinions 50 and 51 are loosely mounted on a rock shaft 52 which is carried by the arm 49 and an arm 53, see Figure 6, said arm being 40 fixed to the shaft 46.

The pinion 51 meshes with two pinions 54 which are mounted on the shafts 55 which carry the vibrator rolls 56. These shafts 55 extend 45 beyond the frame 57 and are journalled in it. This frame is of skeleton construction, as best seen in Figure 5.

The vibrator rolls 56 are in frictional engagement with inking rolls 58, the shafts of which 50 are mounted on journals 60, carried by the frame 57, see more particularly Figure 5.

A gear 60 is connected with the gear 50 and 51 to revolve in unison therewith. The gear 60 is best seen in Figures 5 and 6. The gear 60 meshes with a gear 61 mounted on a shaft 62, 55 which is journalled in the frame 57, in any desired manner. The shaft 62, carries at its other end a worm 63 which is in mesh with the worm wheel 64, mounted on the shaft 65, journalled in the frame 57. A shaft 65 has a disc 66, which has a T shaped slot 67 which adjustably carries a stud 68 which acts as a crank pin for the connecting rod 69, and which at its outer end is pivotally connected with a bracket 70.

The bracket 70 is mounted on a tube 71 which is loosely mounted on a shaft 52, journalled in the arms 53 and 49, and the frame 57 is also fixed to this shaft 52.

The tube 71 has fixed to it at its outer end 70 a double fork 73, the ends of which are received in the grooves 74 at one end of the vibrator rolls 56, so that during the reciprocation of the connecting rod 69, the vibrator rolls will have imparted to them a reciprocatory movement. The travel or length of stroke of the vibrator rolls 75

can be adjusted by adjusting the position of the stud 68 in the slot 67, by means of a fastening device 75.

76 designates the ink fountains, which are of any desired or conventional construction, and which are carried by an auxiliary frame 77 secured to the main frame 1, see more particularly Figure 4. Each ink fountain is provided with a fountain roll 78, an intermediate composition roll 79, and a doctor roll 80, all of which are constructed and operated in the usual and well known manner.

Provision is made for bringing a set of inking rolls 58 into the path of a predetermined impression form. This is accomplished in the following manner.

The shaft 46, see Figure 4, has what may be called a floating fulcrum, and connected to it are the arms 49 and 53 and also an arm 81 which carries a roller 82, which is in the path of a cam 83 fixed to a shaft 84. The arm 81 has fixed to it, one end of a spring 85, the opposite end of which is fixed to a stationary portion of the frame 77 so that the tendency of the spring is to retain this roller 82 in engagement with a cam 83.

The shaft 84 is driven from the pinion 40, as will now be explained, reference being directed to the right hand portion of Figure 4.

30 The pinion 40 meshes with a gear 85 which is fixed to a pinion 86, and this gear and pinion are mounted on a stud 87 carried by the frame. The gear 86 meshes with a gear 88 fixed to a pinion 89, and the gear 88 and pinion 89 are mounted on a stud shaft 90, carried by the machine frame.

35 The pinion 89 meshes with a pinion 91, journalled on a stud 92 and meshing with a gear 93, loosely mounted on the shaft 46. The gear 40 93 meshes with a gear 94 fixed on the shaft 84, thereby causing the drive of the cam 83.

The shaft 84 also carries a closed cam 95 into the groove of which fits the roller 96 carried by the arm 97, the lower end of which is fulcrumed to the machine frame by the stud 93. A link 99 connects the arm 97 to a ratchet arm 100, the opposite end of which is connected by a link 101 to another ratchet arm 102 of the next fountain. The ratchet mechanism feeds a predetermined amount of ink from the fountain to its rolls and is constructed and operated in the usual and well known manner, so that detailed description of its construction and operation is unnecessary.

55 The arrangement of the ratchet mechanism is such that one cam effects the feed of both fountains, and during the operative stroke of a ratchet mechanism for one fountain, the ratchet mechanism for the other fountain is making its 60 inoperative stroke.

The turnover mechanism for the inking rolls

In my present invention, I provide turnover mechanism for the inking rolls so that the turnover is effected by a continuous rotation of the controlling elements and thus eliminating the necessity of employing reciprocating or oscillating parts, and thus one is able to run the inking mechanism at a much higher speed. I also eliminate in a large measure the vibration to which machines of this character are subjected, due to the reciprocatory and oscillatory movements.

The turnover mechanism is controlled and timed by a disc 103 forming a driver which is loosely mounted on a shaft 46, but is connected

with the gear 93 to revolve in unison therewith.

The disc 103 drives a disc 104 forming an indexing device, which is keyed to the rock shaft 52, and the frame 57 which carries all of the inking rolls is also keyed to this rock shaft 52. 5

The disc 103 is provided with three pairs of rollers 105, arranged in spaced relationship around the periphery of the driving disc 103.

In the present machine, the inking mechanism is shown in such a manner that one set is provided for two intermittent movements during one revolution of the disc 103.

During the rotation of the disc 103, the lead roller of a pair of rollers 105 enters into one of the slots 106 on the disc 104 which is tangentially disposed on the center line of the rollers, and these slots are arranged in pairs and are disposed around the disc so that center lines between the slots are 120 degrees apart, so that during the operative movement of a pair of rollers 105, 20 the disc 104 has imparted to it one-third of a revolution, except on the last portion of the revolution. Two-thirds of a revolution is imparted to the disc 104 instead of a one-third revolution, due to the spacing of the pairs of rollers on the 25 disc 103.

This partial revolution of the disc 104 causes a different set of inking rolls to be brought into operative position with respect to the next impression form which is to receive color. 30

I provide novel means for locking the inking mechanism in the position to which it has been adjusted so that during inking, a pair of inking rolls are positively locked in their inking position. For this purpose I provided between each 35 pair of slots 106 a locking roll 107, and, during the period in which a set of inking rolls are locked, these rolls 107 ride on the periphery of the disc 103, as shown in Figure 8.

Between each pair of rollers 105, the disc 103 40 which carries them is provided with a recess or pocket 108, and, during the turnover movement of the inking mechanism, these rollers are received in one of said pockets as will be clearly understood by reference to Figure 10. 45

The walls of the slots 106 nearest to the center line of the two slots are provided with curved clearances for the rollers to clear while going in and out of the slots. The disc 103 has cam portions 109 so that at the time of finishing or 50 starting of the turnover movement, and as heretofore explained, the center walls of the slots being curved for clearance, a space or gap 110 is left, as shown in Figure 8. A roller 107 slides on the cam 109 on the disc, thereby eliminating 55 the lost motion which would have been caused by the gap 110 if the cams 109 were not present.

The rollers 107 are mounted in such manner that they can be adjusted to compensate for wear. In order to accomplish this without upsetting 60 the accuracy of the machine or changing the relative position of the rollers from their location of 120 degrees apart, I provide two holes 111, in the disc 104 which are disposed 120 degrees apart. The arm 49 is provided with a single 65 hole 112, and a pin 113 is provided, which is adapted to extend through the selected holes 111 and into the hole 112, thereby positively locking the disc 104 with respect to the arm 49, then, while the disc 104 is in a fixed position with 70 respect to 49, the rollers 107 are radially adjusted.

For this purpose, the disc 104 is provided with radial slots 114 through which pass the studs 115, which are fixed in position by means of 75

nuts 116, so that the position of the rollers 107 can be adjusted to compensate for any wear to which they have been subjected.

In the type of machine herein shown, five impression forms are employed, and it is therefore necessary to employ five fountains with their co-operating inking mechanisms, it being understood that for each impression form, an inking mechanism is essential so that it will receive its color.

The set of inking mechanisms for the last of the set of five impression forms, is located as herein shown, in proximity to the impression cylinder, as will be best seen from Figures 1 and 3.

The gear 21 meshes with a gear 118 carried by a shaft 119, journalled in the machine frame. A gear 120 is fixed to the gear 118 to revolve therewith, and this gear meshes with an idler 121, suitably journalled and meshing with a gear 122, fastened at the end of the vibrator shaft 123.

The vibrator 124 carried by the vibrator shaft, is in frictional engagement with the inking rolls 125, which are journalled in oscillatory arms 126. The shaft 119 has fixed to it, one end of an arm 127, which carries a roller 128, which is in engagement with a cam 29, fixed to the shaft 84.

130 designates an ink fountain. 131 is the fountain roll. 132 is a doctor roll. The means for producing the proper movement of the vibrator roll is best seen in Figures 1 and 12.

The shaft 84 is provided with a cam 133 having a cam groove with which a roller 134 cooperates, said roller being carried by a rock arm 135, mounted on a boss 136, carried by the machine frame. This rock arm 135 at its upper end, is provided with a fork, to engage an annular groove 137 on the vibrator roll, so that as the arm 135 is rocked the vibrator roll will be reciprocated.

The sheet delivery mechanism is provided with a pair of chains 138, see Figures 1 and 2, which pass around sprocket wheels 139 on the shaft 32. These chains 138 also pass around sprocket wheels on the shaft 140, which is the shaft which carries the sprocket wheels 31 at the delivery end of the machine.

Each chain 138 are block chains in construction, and, on the blocks, are provided with upwardly extending needle points 141. The purpose of these needle points is to support a sheet being delivered with the printed side down, so that the printed side will be supported on the needle points instead of on the chain, and there will be no possibility of blurring the printing on the paper.

The speed of these needle chains having the needle points, are exactly the same as the chains carrying the grippers, thereby causing them to travel as a unit, and the needle points come in contact with the printed sheet at one point will constantly remain at that one particular point without pulling or scratching. This construction is more clearly shown in Figures 1 and 2.

The operation of my novel multi-color printing press will now be apparent to those skilled in this art and is as follows.

The sheets to be printed are fed into the machine in any desired manner, and for the sake of simplicity, I have shown a machine adapted to be fed by hand, although, as is apparent, any desired type of feeding mechanism can be attached to the machine.

Assuming now that the sheets are fed by hand, the sheets 25 are fed one at a time against the front guide or stop 24. Assuming now that the

motor 17 is driving the main driving shaft 13, it will be apparent from Figures 1 and 3 that a drive will be imparted to the shaft 10 and through the gears 11 and 21 to the impression cylinder 19. The grippers act in the well known and conventional manner to grip the sheet which has been fed to the impression cylinder, so that the fed sheet will be carried around the impression cylinder during the revolution of the latter.

The type beds 4, which carry the impression forms 18, have a continuous movement imparted to them, since the gear 9 is, at all times, meshing with a rack 8 secured to the bottom of a type bed, the arrangement being such that when the rack of one type bed moves out of engagement with the driving pinion 9 the rack 8 of the next type bed will come into engagement with such driving pinion 9. The type beds are all connected together by means of a link connection, as hereinbefore described, so that all of the type 20 beds move at the same time and have a continuous movement imparted to them.

In the present construction, I have shown three sets of inking mechanism, A, B, and C respectively. The sets A and B are each provided with 25 two pairs of inking rolls, while the set C is provided with a single pair of inking rolls.

As shown in Figure 4, set A of the inking mechanism has a pair of inking rolls in inking position, while the inking rolls of set B has both 30 pairs of inking rolls out of their inking position.

As the shaft 13 is being continuously driven, the pinion 40, carried by it, drives the gear 85 as well as the gear 41. The gear 41 drives the gear 43 which is similar to the gear 85, both being 35 alike in size and construction of their teeth.

The gear 43 drives the gear 45, which is loosely mounted on the shaft 46 and drives the gear 47, which in turn drives the gear 50. The gear 50 and 51 are connected to rotate in unison, and 40 the gear 51 meshes with two gears 54. The gears 54 are attached to the ends of the vibrator shafts 55 which carry the vibrator rolls 56. These vibrator rolls 56 are in frictional engagement with the inking rolls 58, so that each pair of inking 45 rolls 58 is being driven at the same peripheral speed as that of the type bed which is passing beneath them. Each set A and B of the inking mechanism has the same driving means for the inking rollers, and in Figure 4 at the left hand 50 side of the figure, I have shown the driving means for the inking rolls, while at the right hand side of this Figure 4, I have shown only the driving means for the turnover mechanism.

In the construction illustrated, the arrangement is such that the first impression form receives its color from a pair of inking rolls of the set A. The second impression form receives its color from a pair of inking rolls of set B. The third impression form receives its color from a 60 pair of inking rolls of set A. The fourth impression form receives its color from a pair of inking rolls of set B, and the fifth impression form receives its color from the pair of inking rolls of set C.

In other words, each impression form has its own set of inking rolls and at a selected time receives its proper color.

Operation of inking rolls

While a pair of inking rolls of set A, for example, is applying ink to one impression form, see Figure 4, the cam 23 of set B rocks the arm 81 to raise the frame 57 and a pair of inking rolls 58 out of its operative position, and, at this time, 75

the turnover mechanism for set B is operated to bring its other pair of rollers into position for the next inking operation of set B.

The operation of the turnover mechanism

5 The disc 103 is continuously revolving in the same direction, see Figure 4, and the parts are so timed that one revolution of a disc 103 represents one cycle of the machine. Referring now 10 to Figures 8, 9, and 10, in Figure 8, the parts are shown in position to begin the turnover operation, and the duration of the inking period and of the turnover period are indicated on this figure.

15 A roller 105 is entering a slot 106 in the disc 104, causing it to revolve. These slots 106 are not radially disposed. A pair of slots 106 and a pair of rollers are employed, as best seen in Figure 10, in which figure a pair of rollers 105 are engaged in the slots 106. The main object 20 in using this arrangement is to provide a gradual start and stop of the disc 104 which carries with it the heavy sets of inking rolls, thereby eliminating shocks and jars, and enables the machine 25 to run at a higher speed.

Locking means for disc 104

30 The disc 104 which carries the inking rolls and determines their inking position is provided when a positive locking device which locks the inking rolls in a positive stationary position which eliminates any possibility of roller marks on the impression forms, as will be clear to those skilled in this art. A disc 104 carries three radially disposed rollers spaced 120 degrees apart. The disc 35 103 turns the disc 104 one-third of a revolution, and the next step two-thirds of a revolution, and therefore the locking rollers 107 are in positions to which it has been moved. Two of the rollers 40 107 travel on the periphery of the disc 103 during the inking period, thus locking in position the operative pair of inking rolls.

Unlocking operation of disc 104

45 During the revolution of a disc 104, a pocket 108 on the disc 103 is brought into the path of a roller 107 which enters said pocket, see Figure 10. The pockets 108 provide clearance for the rollers 107 when the disc 104 is unlocked.

50 The sets A and B have two sets of inking rolls set in position 120 degrees apart, see Figure 5. Since the turnover movement is a continuous rotary motion, it will take a one-third revolution to bring one set or pair of inking rolls into operative 55 position, and two-thirds of a revolution to bring the other pair or set of inking rolls into operative position.

Operation of set C of inking rolls

60 The inking rolls 125, see Figure 3, are frictionally driven as hereinbefore explained in detail. At the proper time, the cam 129 rocks the rock arm 127, bringing the inking rolls 125 into operative position and also raises the rolls at the proper time and retains them for the desired period in their inoperative position.

Operation of delivering the printed sheets

65 When the grippers 22 of the impression cylinder 19 contact with the gripper releasing member in the usual and conventional manner, which it is not necessary to show or describe, the front end of a sheet is released from the impression cylinders, and the stripper 26 strips the sheet from the cylinder and transfers it to the deliv-

ery grippers 27 which are moved into their sheet receiving position by the cam 28, see Figure 3.

70 The gripper fingers are carried by the chain 30 which is continuously driven, as before explained. As seen in Figures 1 and 2, the conveyor proper, consisting of the chains 30, has disposed within it the chains 138 which are driven at the same speed and provided with the needle points 141. Each of the chains 30 has a gripper. The needle points prevent the printed 10 face of a sheet contracting with the chains or the conveyor shafts, and also provides a proper support for a sheet as it passes around the loop at the end, see Figure 1. The grippers 27 are released by the cam 35, and the sheet drops 15 printed side up on the receiving table 37. This table may be automatically lowered step by step in the usual and conventional manner.

The impression cylinder makes four revolutions and during the fifth, or last revolution, the 20 printed sheet is delivered. The sheet is delivered during the fifth revolution of the impression cylinder so that it is not necessary to have an idle type bed or a dwell between type beds, thereby materially increasing the output or capacity 25 of the machine, without increasing the length of the cycle.

My present application is a division of my application, Serial No. 203,880, which eventuated 30 into Patent No. 1,879,597.

It will now be apparent that I have devised a new and useful inking mechanism for multi-color printing presses which embodies the features of advantage enumerated as desirable in the statement of the invention and the above 35 description, and while I have, in the present instance, shown and described a preferred embodiment thereof which will give in practice satisfactory and reliable results, it is to be understood that this embodiment is susceptible of 40 modification in various particulars without departing from the spirit or scope of the invention or sacrificing any of its advantages.

Having thus described my invention what I claim as new and desire to secure by Letters Pat- 45 ent, is:—

1. In a multi-color printing press, sets of inking mechanisms, each set having a pair of inking rolls mounted on a support which is rotatable about an axis remote from the axes of the 50 printing rolls, and continuously revolving means revolved into intermittent driving relation with said rolls to progressively move the inking rolls of said sets into and out of their inking positions.

2. In a multi-color printing press, sets of inking mechanisms, each set having a pair of inking rolls mounted on a support which is rotatable about an axis remote from the axes of the 55 printing rolls, and continuously revolving means 60 revolved into intermittent driving relation with said rolls to progressively move the inking rolls of said sets into and out of their inking positions and means to lock said rolls when in inking position.

3. In a multi-color printing press, a pair of inking rolls, a support for said rolls rotatable about an axis remote from the axes of said rolls, a continuously revolving driver, and a member intermittently revolved by said driver 70 and connected with said support to cause said inking rolls to move into and out of their inking position.

4. In a multiple-color printing press, sets of inking rolls, each set having a pair of inking 75

rolls and a support rotatable on an axis remote from the axes of the rolls, a continuously revolved driving disc, and a driven disc intermittently driven by said driving disc to selectively position one of said pairs of inking rolls in inking position.

5. In a multiple-color printing press, sets of inking rolls, each set having a pair of inking rolls and a support rotatable on an axis remote from the axes of the rolls, a continuously revolved driving disc, a driven disc intermittently driven by said driving disc to selectively position one of said pairs of inking rolls in inking position and locking rolls carried by said driven disc and locking with said driving disc to lock a pair of inking rolls in inking position.

6. In a multi-color printing press, sets of inking rolls mounted for rotation about an axis remote from the axes of the rolls, a continuously revolving driver, a driven member intermittently driven by said driver and connected with said support to cause two intermittent turn over movements of said inking rolls during one revolution of said driver.

7. In a multi-color printing press three sets of inking rollers, two of which have two pairs of rolls and the third of which has a single pair of rolls, and means to bring a pair of rolls of each set into inking position in selected timed relation with each other.

OSCAR H. BANKER.
